[57] CLAIM

The ornamental design for a disposable immunoassay reaction tray, as shown and described.

DESCRIPTION

FIG. 1 is a perspective view of a disposable immunoassay reaction tray showing our new design; FIG. 2 is a top plan view thereof; FIG. 3 is a front elevational view thereof, the rear elevational view being identical thereto; FIG. 4 is a bottom plan view thereof; FIG. 5 is a side elevational view thereof; and, FIG. 6 is a side elevational view thereof, opposite that shown in FIG. 5.

FIG. 2FIG. 3FIG. 5FIG. 6FIG. 4
